US00D763136S

(12) **United States Design Patent**
Minami

(10) **Patent No.:** US D763,136 S
(45) **Date of Patent:** ** Aug. 9, 2016

(54) **AUTOMOBILE, TOY REPLICA AND/OR OTHER REPLICAS**

(71) Applicant: **Honda Motor Co., Ltd.**, Tokyo (JP)

(72) Inventor: **Toshinobu Minami**, Wako (JP)

(73) Assignee: **Honda Motor Co., Ltd.**, Tokyo (JP)

(**) Term: **14 Years**

(21) Appl. No.: **29/520,899**

(22) Filed: **Mar. 18, 2015**

(30) **Foreign Application Priority Data**

Sep. 24, 2014 (JP) 2014-021096

(51) **LOC (10) Cl.** 12-08

(52) **U.S. Cl.**

USPC **D12/92**

(58) **Field of Classification Search**

USPC D12/86, 90, 91, 92, 98; 296/37.6, 296/181.1, 181.5, 183.1; D21/424, 433, D21/434

CPC B62D 25/00; B62D 25/06; B62D 33/00; B62D 35/00

(57) **CLAIM**

The ornamental design for an automobile, toy replica and/or other replicas, as shown and described.

DESCRIPTION

FIG. 1 is a front perspective view of an automobile.

FIG. 2 is a rear perspective view thereof.

FIG. 3 is a right side elevation view thereof.

FIG. 4 is a left side elevation view thereof.

FIG. 5 is a front elevation view thereof.

FIG. 6 is a rear elevation view thereof; and,

FIG. 7 is a top plan view thereof.

The broken lines shown in the drawings illustrate portions of the automobile that form no part of claimed design.

1 Claim, 7 Drawing Sheets
